SHOE

Arthur J. Brauer, Webster Groves, and Frederick P. Wagner, St. Louis, Mo.

Application September 16, 1936, Serial No. 100,968

6 Claims. (Cl. 36—45)

This invention relates generally to shoes and particularly to the construction of a shoe having a tongue constructed and arranged to relieve discomfort at the throat of the shoe.

5 In the application of the features of the Wagner Patent No. 2,005,071 to shoes of the Oxford type which embody a tongue, difficulty has been experienced in arranging the parts of the shoe so as to prevent the tongue from interfering with, 10 or minimizing, the effect of the yieldable throat construction. This problem has also been encountered in connection with shoes, the throat portions of which were rendered yieldable in accordance with other well known and conventional 15 methods but heretofore the assembly of the tongue of such shoes together with the upper section in the region of the throat line has tended to obviate the benefits which would otherwise have been derived from such resilient or yield- 20 able throat constructions.

The object of the present invention, generally stated, is to provide a shoe having a tongue so constructed and connected to the adjacent shoe parts that yieldability at the throat line may 25 be secured.

Another object of the present invention is to provide a shoe of the Oxford type having a yieldable throat portion and having a tongue extending above and below the throat portion without 30 interfering with the yieldability of the throat.

Other objects will become apparent to those skilled in the art when the following description is read in connection with the accompanying drawing, in which:

35 Figure 1 is a side view of the forepart of a shoe constructed in accordance with the present invention, part being broken away to reveal the relation of the parts in section.

Figure 2 is a plan view of a part of a vamp 40 assembly employed in accordance with one embodiment of the present invention.

Figure 3 is a bottom plan view of the assembly shown in Figure 2.

In accordance with the present invention, a 45 shoe, such for instance as one of the Oxford type which is provided with a tongue, may have its throat portion rendered yieldable or resilient in any suitable manner as, for example, by treating it as set forth in the Wagner Patent No. 50 2,005,071. In accordance with the present invention, however, where such yieldable throat features are to be employed in shoes having tongues, the tongue is connected to the outside vamp sections only at points removed from the 55 yieldable throat line. For instance, in accord-

ance with one embodiment the tongue member is arranged to extend both forwardly and rearwardly of the throat line but is not directly connected to the outside upper section which has been rendered yieldable at the throat in the yieldable 5 region. On the other hand, in order to secure the tongue member in position it may be connected directly to the outside vamp section beyond the extremities of the yieldable region in the latter, or, it may be connected to the lining 10 for the vamp and the lining in turn connected to the vamp so as to provide for substantial flexibility and movement between the tongue member and the outside upper section, such as the vamp which has been made yieldable at the 15 throat, and thereby avoid rigidity which, to some extent at least, would mitigate the effect of treating the outside vamp section in accordance with the Wagner Patent No. 2,005,071.

Referring now particularly to the drawing for 20 an illustrative embodiment of the present invention a shoe of the Oxford type is shown in which a vamp section 1 is connected to quarter sections 2. The quarter sections 2 are provided with lace stays 3 and a tongue 4 is arranged to underlap 25 lace stays 3 in the usual manner so as to provide an Oxford.

In the embodiment shown, vamp 1 is treated 30 in accordance with the Wagner Patent No. 2,005,071 so as to provide a yieldable region at the throat line 5 thereof. As pointed out in said Wagner patent, this may be accomplished by providing a tab at the throat line which may be folded under to embrace a piece of elastic 6 and be slit, as shown at 7, across the fold in order 35 to provide ample yieldability.

In the embodiment shown the vamp is provided with a lining 8 which may be of any suitable material, either textile or leather, but for the purpose of illustration the lining 8 will be considered as textile material. As shown clearly in Figure 3, lining 8 terminates ahead of throat line 5, the upper terminus of lining 8 being shown in dotted lines and indicated as 9 in Figure 3.

Tongue piece 4 may be connected to lining 8 40 as by means of a line of stitching 10, or otherwise, substantially in front of throat line 5 and tongue piece 4 may be connected directly to the outside vamp section 1 at the sides of the throat 45 beyond the resilient region as by lines of stitching 11. It will be observed that, although the tongue member 4 is stitched to the outside vamp section at each extremity of the yieldable throat region, there is no direct connection between the 50 55

tongue member and the outside vamp section immediately at the resilient region of the latter.

In the event that lining 8 is made of leather, or other material suitable for forming the tongue, or tongue lining, it will be understood that lining 8 may include the tongue lining as a part thereof and hence connection of this member with the outside vamp by lines of stitching 11 only may be required.

10 In order to render the shoe construction as resilient as feasible in the region of the throat and to further insure that the tongue construction will not interfere with the yieldability of the outside member, the tongue may be provided with a series of longitudinally extending slits 12 arranged in sidewise relation at the part thereof which, in the finished shoe, will lie directly beneath the yieldable throat region 5. The provision of such slits permits the tongue member 4 to stretch laterally at that point upon yielding of the outside vamp member 1 and, when the slits are arranged, as shown in the drawing, they are not discernible by casual observation of the shoe because of the fact that they are substantially concealed by the overlapping part 5.

25 From the foregoing description it should be apparent that the present invention accomplishes its objects and provides a shoe of the type having a tongue wherein the throat portion of the exterior upper materials may be treated in order to provide yieldability in that region. Furthermore the tongue of the shoe may be so arranged that it does not interfere with the action or function of the yieldable outside part.

30 While in the foregoing description a disclosure of one illustrative embodiment of the present invention has been given, it is not to be understood that the invention is limited to the precise arrangement of parts hereinbefore described or 40 shown in the accompanying drawing, but, on the contrary, it is realized that various modifications will present themselves to those skilled in the art without departing from the spirit of this invention. It is to be distinctly understood, therefore, 45 that such modifications and the use of such individual features and subcombinations of features as do not depart from the spirit of this invention are, although not specifically described herein, contemplated by and within the scope of the appended claims.

Having thus described the invention, what is claimed is:

1. A shoe comprising, an outside vamp section, a continuous vamp lining, and a tongue medially connected to the lining, said outside vamp being free of connections with the lining and tongue medially of the latter. 5

2. A shoe comprising, an outside vamp section arranged to provide a throat line, said vamp being yieldable at the throat line, a continuous lining for said vamp, said lining being cut to provide a throat lower than the throat line of said outside section, said lining being connected to said vamp only at regions remote from the middle of the throat line. 10

3. A shoe comprising, an outside vamp section arranged to provide a throat line, said vamp being yieldable at the throat line, lining material for the outside vamp terminating short of said throat line, and connected to the vamp only at 20 regions remote from the middle of the throat line and a tongue piece connected to said lining adjacent the throat thereof but disconnected from said outside vamp section adjacent the throat thereof. 25

4. A shoe comprising, an outside vamp section arranged to provide a throat line, said vamp being yieldable at the throat line, a tongue having a part underlapping said throat line but disconnected from the vamp thereat, and a lining member connecting said tongue to said vamp in regions remote from the middle of said throat line. 30

5. A shoe comprising, an outside vamp section arranged to provide a throat line, said vamp being yieldable at the throat line, a tongue having 35 a part underlapping said throat line, said tongue having a series of longitudinally extending slits adjacent the throat line, and means connecting said tongue to said vamp only in regions remote from the middle of said throat line. 40

6. A shoe comprising an upper having a tongue piece extending forwardly and rearwardly of the throat of the shoe, said tongue piece having a series of longitudinally extending slits arranged in substantially parallel relation adjacent the 45 throat, and means connecting said tongue piece to the upper only at points substantially spaced from the throat middle.

ARTHUR J. BRAUER.
